PRESSURE JET TANK CLEANER

BACKGROUND OF THE INVENTION

This invention relates to a tank cleaner and, more particularly, to a device for directing strong jets of cleaning fluid in directions determined by a hydraulically operated turbine and gearing drive immersed in the fluid.

Cargo tanks of the marine trade and also mobile as well as stationary tanks for land use are often cleaned when their inner walls have been in contact with oil or other stored liquids. The cleaning task is usually one involving a toxic, greasy, vaporous, explosive, or high temperature condition. It has been common in the past to suspend a hydraulically rotated nozzle head in a given tank so that high-pressure jets of suitable cleaning fluid could be directed on all inner wall surfaces to dislodge the dirt and avoid risks and also the extended labor necessarily involved if the task were manually performed as in former years. Such a nozzle head device performs the cleaning task admirably, and examples of such devices are disclosed in the U.S. Pat. Nos. 3,255,969 granted June 14, 1966 and 3,275,241 granted Sept. 27, 1966, each in the name of Michel A. Saad, and also in the U.S. Pat. No. 3,326,468 granted June 20, 1967 in the names of Robert A. McCloud and Barney Bristow.

It has now been found that such a hydraulically operated device need not be as heavy, complicate or costly as those disclosed in the above-referred-to patents or previously in use, and also that it may be relatively free of maintenance and repair despite protracted use periods. An excellent device may be made using a simple and commercially available T-fitting in place of the costly and complex housing heretofore employed as a main element. It has also been discovered that thrust bearing problems may be eliminated thereby further reducing cost and enhancing compactness of structure and lightness in weight. These factors contribute much to handling ease.

An object of the present invention is to provide an improved tank cleaner which is light in weight, simple in construction, low in cost and substantially devoid of maintenance difficulties and, at the same time, is fully effective in performing the tank cleaning function.

A feature of the present invention is a fluid supply means such as a support sleeve, a nozzle head and an interposed housing in which the housing contains a turbine and gearing in contact with and driven by the fluid being supplied and effective to impart dual rotational movement to nozzles diverging from the nozzle head.

The above and other important features of the invention will now be described in detail and pointed out more particularly in the appended claims.

BRIEF DESCRIPTION OF THE DRAWINGS

FIG. 1 shows an elevation view of a railroad tank car with a portion broken away to depict a cleaner device in a functional position;

FIG. 2 is a cross-sectional view, drawn to a larger scale, of a cleaner device embodying features of the present invention; and

FIG. 3 is a perspective view, drawn to an intermediate scale, and illustrating a preferred exterior appearance of the device shown in FIG. 2.

DESCRIPTION OF THE PREFERRED EMBODIMENT

In FIG. 1, a railroad car tank 2 is shown with a cleaner device 4 supported in functional position on the lower end of a fluid supply conduit 6. The device 4 is adapted to rotate on a first or vertical axis simultaneously with rotation of nozzles 82 and 84 of the device on a second or horizontal axis. It is clear that the multidirectional positions thus given to the nozzles 82 and 84 will cause jets of cleaning fluid emanating from the nozzle strongly to impinge against the interior surfaces of tank 2 and perform the cleaning operation.

In FIG. 2, a duct or support sleeve 10 is provided with threads 12 by means of which it can be detachably held or

suspended from a cleaning fluid supply duct or hose 6 such as shown in FIG. 1. The sleeve 10 has an inner annular shoulder 14 and an outer annular shoulder 16 facing in opposite directions. The lower end of the sleeve 10 is formed with bevel gear teeth 18, and it also bears an outer annular groove 20 retaining an O-ring 22.

A bladed stator 24 fits within the sleeve 10 with a slight peripheral clearance as at 26 and 27, and also is made with an annular shoulder 28 facing the sleeve shoulder 14. Fixed to and coaxial with the stator 24 is a rod or tension member 30 which depends downwardly into a large L-shaped portion 32 and a smaller bottom portion 34 of a T-shaped chamber. The latter is defined by the support sleeve 10, a nozzle head 36, and a preferably, but not necessarily T-shaped housing 38 interposed between the sleeve and head.

Coaxially and rotatably mounted on and with respect to the rod 30 and adjacent to the stator 24 is a turbine rotor 40. A drive sleeve or shaft 42 is fixed to and depends from the rotor 40 and bears a plate 44 beveled at its periphery merely in the interest of compactness. The plate carries at least one pin 46 upon which a two-part planetary gear 48 may rotate. Upper and lower portions 48a and 48b of gear 48 are provided with different numbers of teeth, and each is in engagement with a gear 50 or 52 mounted on the rod 30. Gear 50 is a sun gear keyed at 51 to the rod, whereas the gear 52 is integral with a plate 54 keyed at 56 to the housing 38 but free to rotate on the rod 30. A first closure 58 is fixed at 60 to the lower end of the rod 30, and bears an O-ring 62 forming a seal with the housing 38. A plastic bearing ring 64 is also provided between the housing 38 and the first closure 58 merely to avoid any incidental friction due primarily because of the weight of the power rotated parts. Suitable plastic bearings 66, 68, 70, 72 and 74 are provided to minimize friction encountered in the rotation of the gears. These plastic bearings should be of material capable to resist specific conditions of use to be encountered.

The third or side leg of the T-shaped housing 38 telescopically receives a reduced portion of the nozzle head 36 and with an O-ring seal 76 and a plastic bearing 78 interposed. The inner end of the head 36 is provided with bevel gear teeth 80 held in engagement with the teeth 18 of the support sleeve 10. Outwardly directed nozzles 82 and 84 extend from the nozzle head 36. A second closure 86 is nonrotatively held with respect to the housing 38 by means of a tension member or strap 88 apertured at 90 to either clear shaft 42 or to receive a bushing 91 in which shaft 42 rotates. Interposed between the second closure 86 and head 36 is an O-ring seal 93 and a plastic bearing 92.

Assuming that the device 4 is permanently or temporarily supported within a tank 2 to be cleaned and it is retained on a cleaning fluid supply conduit 6 of some sort as shown in FIG. 1, it will be seen that fluid under high pressure acts against the closure 58 placing rod 30 under tension, and thereby forcing stator 24 downwardly causing clutchlike engagement of surfaces 14 and 28. Since surface 28 is fixed, this clutchlike engagement holds stator 24, closure 58, and sun gear 50 against rotation. With the fluid supply cut off, however, or in the event the cleaning device 4 is subjected to shock, a clutch release or slipping action permits the device 4 freely to turn about the vertical axis. If the supply of fluid continues and with no obstruction to impede the action, the gears in the chamber portion 34 will turn as driven by the turbine rotor 40 and the plate 54 will rotate the housing 38 about the vertical axis. The engagement of the teeth 18 and 80 will, in turn, cause rotation of the nozzles 82 and 84 about a horizontal axis.

The epicyclic or compound planetary gear arrangement is such that with each revolution of the planetary gear 48 about the fixed sun gear 50, the gear 48 rotates about its own axis and with less teeth in the gear part 48b than in the gear part of 48a, the gear 52 and hence the housing 38 will rotate at a much slower rate than will the turbine rotor 40. As shown, and merely by way of example, fifty revolutions of the rotor 40

could result in a single revolution of the nozzle head 36 about a vertical axis and simultaneous rotation of the nozzles 82 and 84 about a horizontal axis at a rate dependent upon the revolutions of the housing 36 about the axis 94 and the ratio of the pitch diameters of the gear teeth 18 and 80.

Thrust bearing loads are insignificant as fluid pressure exerted against the closures 58 and 86 are balanced through the tension members 30 and 88 against other parts of the system with heretofore used costly and troublesome thrust bearings being avoided. Also, no separately sealed and grease filled gearing chamber is used, and the gearing is immersed in and lubricated by the cleaning fluid so that compactness, light weight and simplicity follow as characteristics of the structure.

I claim:

1. A tank cleaning device comprising:
a support sleeve;
a nozzle head and an interposed housing cooperating with
said sleeve and head to form a fluid conducting chamber;
a first closure arranged as a seal for said chamber;
means for holding said first closure in rotatable relation with
said housing;

a bladed stator disposed in said support sleeve and in non-
rotatable relation with said first closure, said nozzle head
being journaled in said housing to form a side fluid outlet
for said chamber;

a second closure rotatably mounted on and in relation with
said nozzle head and forming a seal for said chamber;
means holding said second closure and seal housing in non-
rotative relation;

a turbine rotor adjacent to said bladed stator and rotatable
with relation to the latter; and

a differential reduction gearing arrangement disposed in
said chamber and connecting said turbine rotor to said
housing for rotating the latter around one axis, said differ-
ential reduction gearing arrangement including a shaft
having one end fixed to said turbine rotor and its other
end with the remainder of said gearing arrangement being
rotationally supported on said first closure, adjacent ends
of said nozzle head and support sleeves being geared
together to form a drive connection for driving said nozzle
about a second axis.

2. A tank cleaning device as set forth in claim 1, said fluid
conducting chamber comprising a large L-shaped portion and a
smaller side portion, and the said remainder of said gearing
arrangement being located within said smaller side portion.

3. A tank cleaning device as set forth in claim 1, said sup-
port sleeve and said bladed stator having facing annular
shoulder surfaces coaxial with said turbine rotor and constitut-
ing portions of a frictional holding means for normally holding
said first closure means in nonrotatable relation with said
sleeve, the annular shoulder surface on said stator facing said
housing, and annular radial clearances being defined within
said support sleeve and around said bladed stator and turbine
rotor.

4. A tank cleaning device as set forth in claim 3, said frictional holding means including a rod extending through said differential reduction gearing and effective to serve as a ten-
sion member in transferring a fluid pressure load on said first
closure to said support sleeve through contact of said facing
annular shoulder surfaces.

5. A tank cleaning device as set forth in claim 1, said means
holding said first closure in rotatable relation with said hous-
ing and means holding said second closure and housing in non-
rotative relation being elongated tension elements passing
through said fluid conducting chamber and effective to be ten-
sioned in resisting fluid pressure present in the latter.

6. A tank cleaning device comprising:
a housing;
a fluid supply means and a nozzle head connection together
to define an angular main flow chamber, but each being
relatively rotatable with relation to the others;
first and second closures on said housing and nozzle head
respectively;

tension members retaining said closures in positions to seal
said fluid flow chamber against fluid pressure in the latter,
said tension members including an elongated element
held nonrotatively with relation to said fluid supply means
and said closure, and an elongated element held nonrotat-
ively with respect to said housing and said second clo-
sure; and

means in said fluid flow chamber for imparting dual rota-
tional movement to said nozzle head with respect to said
fluid supply means.

7. A tank cleaning device comprising:
housing means including an upper projection, a lower pro-
jection and a side projection defining a generally T-
shaped fluid flow chamber;

fluid supply sleeve means having gear means provided at
one end thereof, said one end being sealingly received
within said upper projection of said housing means;
generally cylindrical nozzle head means provided with gear
means at one end and being open at the other end, said
one end of head means being sealingly received within
said side projection of said housing means and operatively
engaging said one end of said sleeve means so as to cause
said nozzle head means to be rotated relative to said hous-
ing means when said housing means is rotated relative to
said sleeve means;

first closure means sealingly engaging said lower projection
of said housing means and being rotatable relative
thereto;

first tension means passing through said chamber and
coupling said first closure means to said sleeve means;
second closure means sealingly engaging said other end of
said nozzle head means and being rotatable relative
thereto;

second tension means passing through said chamber and
coupling said second closure means to said housing
means; and

hydraulic drive means disposed within said chamber for
causing said housing means to be rotated relative to said
sleeve means.

8. A tank cleaning device as set forth in claim 7 wherein said
drive means is operatively coupled to said first tension means,
one end of said first tension means being affixed to said first
closure means and the other end thereof including a bladed
stator means frictionally engaging said sleeve means so as to
normally remain static when a fluid is caused to flow through
said chamber, said frictional engagement providing a
clutching means allowing said housing means to be rotated
relative to said sleeve means independently of said drive
means in the event that an external force is applied to said
housing means or said nozzle head means overcoming said
frictional engagement, said clutching means thus reducing the
likelihood of damage to said device.

9. A tank cleaning device as set forth in claim 8 wherein said
drive means include a differential-epicyclic gear means which
is lubricated by the fluid medium caused to flow through said
device.

10. A tank cleaning device as set forth in claim 9 wherein
said drive means includes a rotor means, a sun gear means
secured to said first closure means, a planetary gear means
driven by said rotor means and engaging said sun gear means,
and a housing drive gear means rotatable about a common
axis with said sun gear means and operatively engaging said
housing and said planetary gear means such that said housing
means is caused to be rotated relative to said sleeve means in
response to fluid flow induced rotation of said rotor means.

11. A tank cleaning device as set forth in claim 10 wherein
said nozzle head means includes a plurality of outwardly
directed nozzle means communicating with said chamber for
discharging the fluid passed therethrough.

12. A tank cleaning device as set forth in claim 7 wherein
said drive means includes differential-epicyclic gear means
operatively coupling said housing means to said sleeve means.
